(57) **CLAIM**

The ornamental design for a multi-legged fishing lure, as shown and described.

DESCRIPTION

FIG. 1 is a perspective view of my new ornamental design for a multi-legged fishing lure;

FIG. 2 is a top plan view of the multi-legged fishing lure shown in FIG. 1;

FIG. 3 is a bottom plan view of the multi-legged fishing lure shown in FIG. 1; and,

FIG. 4 is a side elevational view of the multi-legged fishing lure shown in FIG. 1.

The broken lines in the drawings of the multi-legged fishing lure are for illustrative purposes only and form no part of the claimed design.
